UNITED STATES PATENT OFFICE

2,597,198

LIQUID LEVEL CONTROL MEANS

Horace M. Staggs and Louis F. Davis, Dallas, Tex.,
assignors to The Atlantic Refining Company,
Philadelphia, Pa., a corporation of Pennsylvania

Application October 23, 1947, Serial No. 781,582

19 Claims. (Cl. 103—232)

1

This invention relates to improvements in liquid level control means.

More specifically, it involves means for controlling the level of the liquid within a tubing string or conductor of an oil well, the reservoir pressure of which is insufficient to raise the liquid to the well surface, the purpose being to assure lifting of the liquid to the well surface with the aid of auxiliary fluids, for example, air or gas, having maximum available pressures.

In those wells in which the reservoir pressure is insufficient to raise the liquid to the well surface, it is common practice to lift the liquid to the well surface by the injection within the column of liquid of an auxiliary fluid, the point of injection of the auxiliary fluid being within limits dependent upon the normal maximum level of the liquid and the pressure of the fluid. There are on the market a number of known devices for periodically injecting fluid into the column of the well liquid. One such device is commonly termed an "intermitter" device, and more specifically is described in United States patent to H. M. Staggs, No. 1,683,930, dated September 11, 1928, entitled "Air Lift Pump." Another such device is described in United States patent to R. O. Walton, No. 2,385,316, dated September 18, 1945, entitled "Well Flow Device." Still another such device is described in United States patent to J. D. Nixon, No. 2,405,232, dated August 6, 1946, entitled "System and Apparatus for Flowing Wells."

These and other similar devices are being commercially employed with satisfactory results. However, they will at times fail to operate when, for example, due to a sporadic increase in reservoir pressure, the hydrostatic pressure of the liquid is increased in excess of the maximum available fluid pressure. The purpose of the present invention, therefore, is to control the hydrostatic pressure or level of the liquid within a tubing string or well conductor relative to fluid pressure and within the limits of the maximum available fluid pressure, and thereby to insure at all times the operation of the particular lifting means.

Various modifications of this invention will be hereinafter described in combination with the "intermitter" device described in the Staggs patent, No. 1,683,930 above mentioned. It will be apparent, however, that its use is equally applicable in combination with the well flow devices shown in the patent to Walton No. 2,385,316, and the patent to Nixon, No. 2,405,232, and other similar devices.

2

One of the objects of this invention, therefore, is to provide a liquid level control means for accurately controlling the level of liquid within a tubing string or conductor of an oil well, the reservoir pressure of which is insufficient to raise the liquid to the well surface.

Another object of the invention is to provide liquid level control means which may be automatically actuated by the application of auxiliary fluid under pressure, and which automatically will be actuated by alternating differentials between the pressure of the auxiliary fluid and the hydrostatic pressure of the liquid within the tubing string, to admit liquid from the well reservoir into the tubing string or well conductor until a predetermined level of the liquid in the tubing string or conductor has been reached, and when this has been accomplished, to seal off the tubing string or conductor against the admission of additional liquid from the reservoir.

Another object of the invention is to provide a liquid level control means adaptable for use in combination with the "intermitter" means for controlling the level of the well liquid within the tubing string or conductor of an oil well whereby operation of the intermitter means will at all times be assured.

Other objects of the invention will be apparent from the description and claims which follow:

In the drawing like numerals are used to indicate like parts.

Figure 1 is an elevational view, partly in section, of a well structure showing generally the combination of an "intermitter" device and the device of the present invention.

Figure 2 is an enlarged elevational view, partly in section, showing the "intermitter" device.

Figure 3 is a sectional view along line 3—3 of Figure 2.

Figure 4 is a sectional view taken along line 4—4 of Figure 2.

Figure 5 is an elevational view, partly in section, showing one form of the present invention.

Figure 6 is an elevational view partly in section showing a modified form of the invention shown in Figure 5, and in which the valve is closed against the admission of additional liquid from the tubing string.

Figure 7 is a view like Figure 6 with the exception that the valve is shown in an open position.

Referring to the drawings, and in particular to Figure 1 thereof, the numeral 1 represents generally an oil well comprising casing 2, and tubing or conductor 3 secured within casing 2 by conventional means at wellhead 4. The well

1 is produced from reservoir 5 through perforations 6, the liquid entering casing 2 from reservoir 5 being directed into tubing 3 by packer 7. "Intermitter" 8, and liquid level control means 9 are built into tubing 3 and are actuated in a manner hereinafter described, by auxiliary fluid under pressure in annular space 10 between casing 2 and tubing 3. Fluid under pressure is admitted into annular space 10 through pipe 11 from a source not shown.

The "intermitter" device shown in Figures 1, 2, 3, and 4, of the drawings comprises generally housing 12 secured at its opposite ends to tubing 3 by threaded couplings 13 and in which valve 14 is mounted for slidable movement within sleeve 15 secured within axial bore 16 in housing 12 by threaded collar 17. Valve 14 is seated, as at 18, and is normally maintained in a closed position by the action of helical spring 19 distended between shoulder 20 of housing 12 and shoulder 21 of cap 22 threaded to stem 23 of valve 14. Fluid under pressure in annular space 10 is normally maintained against the pressure side of valve 14, through interconnecting port 24 and chamber 25. However, upon opening of the valve 14, the fluid under pressure will be caused to pass through interconnecting ports 26, 27, 28, and 29, and axial bore 30, sealed against chamber 25 by threaded cap 31, and into the liquid in the space of tubing 3 generally designated by the number 32, from which space it will rise through vertical bores or ports 33 in housing 12, and into the body of liquid in the space of tubing 3 generally designated by the numeral 34. Valve 14 is mechanically operated intermittently by the lowering of weight 35 against cap 22, the action of weight 35 being controlled through the medium of wire line 36 and lowering and raising mechanism 37 located at the well surface.

At such times as the volume of liquid above intermitter 8, that is, in the space of tubing 3 generally designated by the numeral 34 is proportionate to the pressure of the fluid, the fluid upon entering such body of liquid will cause the liquid to become aerated, and thereafter it will lift the liquid to the well surface. However, at such times as the volume of well liquid above intermitter 8 is increased in relation to the pressure of the fluid due, for example, to a sporadic increase in reservoir pressure, the intermitter is said to have failed to function because of insufficient fluid pressure to lift the aerated body of liquid to the well surface. The present invention is designed to prevent these failures by at all times controlling the maximum level of the well liquid above intermitter 8.

The liquid level control means shown in Figure 5 of the drawings comprises generally a housing 38 formed of sections 39, 40, and 41, interconnected by threaded couplings 42 and 43, and a valve 44, the action of which is controlled through the medium of a piston 45. The liquid level control means is threaded as at 46, to tubing 3, at a point below "intermitter" 8, and at its lower end is provided with the conventional strainer 47.

Valve 44 is normally maintained in a closed position by the action of helical spring 48, distended between shoulder 49 of housing section 41, and shoulder 50 of cap 51 threaded to valve stem 52, and fixedly secured thereto by locknut 53. Valve 44 is seated, as at 54, against valve sleeve 55 secured within housing section 41 by threaded collar 56. Movement of valve 44 against the action of spring 48 is controlled by piston 45 pro-

vided with sealing rings 57 and mounted for slideable movement within cylinder 58, threaded as at 59 within housing section 39, and in a manner to provide annular space 60 therebetween and housing section 40. Fluid under pressure in the annular space between casing 2 and tubing 3 is at all times directed through open ports 61 and 62 against head 63 of piston 45, and in the operation of the liquid level control means it will be seen that the well liquid is at all times directed against head 64 of piston 45, the pressure thereagainst being dependent upon the hydrostatic pressure of the liquid in the tubing string above the liquid level control means. Therefore, upon release of liquid pressure against head 64, for example, due to operation of "intermitter" 8, it will be seen that piston 45 will be caused to be moved downwardly against nut 53 by the presence of the fluid against head 63, whereby valve 44 will be forced to an open position against the action of spring 48. Valve 44 having been opened, the well liquid within tubing 3 below the valve will flow under reservoir pressure upwardly through chamber 65, ports 66, and 67, into section 40 of housing 38, through annular space 60, through port 68, and into the tubing above the liquid level control means. The liquid entering the tubing above the liquid level control means will rise above the intermitter device through ports 33 and will continue to do so until a level is reached at which a sufficient hydrostatic pressure will be developed whereby the pressure against head 64 of piston 45, with the aid of spring 48 will reverse the pressure differential across piston 45, thereby causing piston 45 to rise and valve 44 to become closed by the action of spring 48. The valve 44, once it is closed, will remain closed until further operation of "intermitter" 8, at which time the pressure differential across piston 45 will again be reversed and the cycle repeated.

The invention as exemplified in Figures 6 and 7 differs from that shown in Figure 5 principally in the use of a bellows 69 in lieu of piston 45 for opening valve 44. More particularly, the device shown in Figures 6 and 7, comprises generally a housing formed of end sections 70 and 71 threaded at 72 and 73, respectively, to central section 74, and at 75 and 76, respectively, to tubing 3. Valve 44 is seated, as at 77, on seat member 78, rigidly secured within housing section 71, by threaded collar 79, which collar 79 also serves as a guide sleeve to valve stem 52, through axial bore 80, and to provide a series of vertical bores or ports 81, for the passage of liquid therethrough. Valve 44 is normally maintained in a closed position by helical spring 48 distended between flanged collar 82 and nut 83 threaded on the free end of stem 52, and rigidly secured thereon by locknut 84. Bellows 69 is secured by welding or in any other suitable manner, as at 85, to floating head 86 and, as at 87, to fixed head 88, the fixed head 88 being rigidly secured as by threading at 89, in the one end of cylinder 90 which in turn is threaded at its opposite end at 91, to flanged member 92 of end section 70, and in a manner providing sealed bellows chamber 93 and annular space 94 therebetween and the inner wall of central section 74. Bellows stem 95 is threaded at 96 to bellows head 86, and adjacent its opposite end is mounted for slideable movement through axial bore 97 in cap 98 threaded at 99 into bellows head 88. A series of bores or ports 100 in cap 98 permit the flow of liquid into and from the interior of bellows 69. Cap 101 is threaded at 102, to the free end of bellows stem

95 and upon compression of bellows 69 will be caused to move downwardly with stem 95 against cap 103, and through the medium of stem 52 to open valve 44. It will be seen that when bellows 69 is in a distended position, cap 101 is brought to rest against cap 103, but that liquid within space 104 within central section member 74 is at all times free to flow into and from the interior of bellows 69 through openings 105 in cap 101, and ports 100 and annular groove 106 in cap 93. It furthermore will be seen that opening movement of valve 44, and consequently the compression of bellows 69 is limited by cap 107 threaded at 108 into end section 71.

Upon opening of valve 44, liquid entering through strainer 109 will be caused to flow by reservoir pressure through openings 110 in cap 107, past valve 44, through ports 81, into space 104 in central member 74, and through annular space 94, and from which it will follow through interconnecting ports 111 and 112 and into tubing 3 above the liquid level control means, and consequently, to a predetermined level above "intermitter" 8 in the manner hereinbefore described. Also the well liquid entering the liquid level control means will be caused to enter the interior of bellows 69 through ports 105 and 100 and annular groove 106 and thus to exert a pressure against the interior of bellows 69 dependent upon the level of the liquid in tubing 3 above the liquid level control means, as against the pressure of the fluid in the annular space 10 which at all times is applied against the exterior of bellows 69 through interconnecting ports 113 and 114 providing communication between the annular space 10 and bellows chamber 93.

Upon operation of intermitter 8, a differential in pressure across the bellows 69 in favor of the pressure of the fluid in the annular space 10 will be brought about, whereby bellows 69 will be compressed and cause bellows stem 95 to be moved in a downwardly direction against cap 103 and valve stem 52, thereby causing valve 44 to be opened and to admit additional liquid to tubing 3 to the predetermined level at which time the differential in pressure across bellows 69 will be reversed in favor of the pressure of the liquid against the interior of the bellows, and the valve 44 closed.

We claim:

1. In a well in a producing reservoir having a pressure insufficient to flow the well liquid to the well surface including a casing, a tubing within the casing, and means for directing the well liquid into the tubing, means positioned within the tubing for controlling the level of the well liquid within the tubing, comprising valve means normally preventing the flow of liquid therethrough, a source of fluid pressure, and pressure responsive means responsive alternately to the fluid pressure and to the hydrostatic pressure of the liquid the level of which is to be controlled, the pressure responsive means being operable upon the application of fluid pressure to open the valve and to maintain the valve in an open position until passage therethrough of a quantity of liquid providing a hydrostatic pressure sufficient to operate the pressure responsive means against the action of the fluid pressure and to permit the valve to close.

2. In a well in a producing reservoir having a pressure insufficient to flow the well liquid to the well surface and including a casing, a tubing within the casing, and means for directing the well liquid into the tubing, means positioned

within the tubing for controlling the level of well liquid within the tubing, comprising valve means normally preventing the flow of liquid therethrough, a source of fluid pressure, pressure responsive means responsive alternately to the fluid pressure and to the hydrostatic pressure of the liquid the level of which is to be controlled, the pressure responsive means being operable upon the application of the fluid pressure to open the valve and to maintain the valve in an open position until passage therethrough of a quantity of liquid providing a hydrostatic pressure offsetting the applied fluid pressure, and means for closing the valve.

3. In a well in a producing reservoir having a pressure insufficient to flow the well liquid to the well surface and including a casing, a tubing within the casing, and means for directing the well liquid into the tubing, means positioned within the tubing for controlling the level of well liquid within the tubing, comprising valve means normally preventing the flow of liquid therethrough, a source of fluid pressure, and pressure responsive means movable in one direction by the application of fluid pressure and in the opposite direction by the hydrostatic pressure of the liquid the level of which is to be controlled, the pressure responsive means opening the valve upon the application of fluid pressure and maintaining the valve in an open position until passage therethrough of a quantity of liquid providing a hydrostatic pressure sufficient to operate the pressure responsive means against the action of the fluid pressure and to permit the valve to close.

4. In a well in a producing reservoir having a pressure insufficient to flow the well liquid to the well surface and including a casing, a tubing within the casing, and means for directing the well liquid into the tubing, means positioned within the tubing for controlling the level of well liquid within the tubing, comprising valve means normally preventing the flow of liquid therethrough, a source of fluid pressure, and pressure responsive means responsive alternately to the fluid pressure and to the hydrostatic pressure of the liquid the level of which is to be controlled, the pressure responsive means comprising a floating piston member movable in one direction by the application of fluid pressure to open the valve and to maintain the valve in an open position until passage therethrough of a quantity of liquid providing a hydrostatic pressure sufficient to move the floating piston in the opposite direction thereby permitting the valve to close.

5. In a well in a producing reservoir having a pressure insufficient to flow the well liquid to the well surface and including a casing, a tubing within the casing, and means for directing the well liquid into the tubing, means positioned within the tubing for controlling the level of well liquid within the tubing, comprising valve means normally preventing the flow of liquid therethrough, a source of fluid pressure, pressure responsive means responsive alternately to the fluid pressure and to the hydrostatic pressure of the liquid the level of which is to be controlled and operable upon application of the fluid pressure to open the valve and maintain the valve in an open position until passage therethrough of a quantity of liquid providing a hydrostatic pressure sufficient to operate the pressure responsive means against the action of the fluid pressure and to permit the valve to close, the pressure responsive means comprising a normally distended bellows,

means for applying the fluid pressure externally of the bellows, and means for applying the hydrostatic pressure internally of the bellows.

6. In a well in a producing reservoir, having a pressure insufficient to flow the well liquid to the well surface and including a casing, a tubing within the casing, and means for directing the well liquid into the tubing, means positioned within the tubing for controlling the level of well liquid within the tubing, comprising valve means normally preventing the flow of liquid therethrough, a source of fluid pressure, and pressure responsive means responsive alternately to the fluid pressure and to the hydrostatic pressure of the liquid the level of which is to be controlled, the pressure responsive means comprising a normally distended bellows, means operably associating the bellows with the valve, means for applying the fluid pressure externally of the bellows whereby the bellows is contracted thereby opening the valve and maintaining the valve in an open position until passage therethrough of a quantity of liquid providing a hydrostatic pressure greater than the fluid pressure, and means for applying the hydrostatic pressure internally of the bellows whereby the bellows will be caused to return to its normally distended position, thereby permitting the valve to close.

7. In a well in a producing reservoir having a pressure insufficient to flow the well liquid to the well surface, including a casing, a tubing within the casing, means for directing the well liquid into the tubing, and means operable periodically and independently of the liquid level in the tubing for lifting the well liquid to the surface of the ground; the combination of means for controlling the level of well liquid within the tubing, comprising valve means normally positioned to prevent the flow of liquid therethrough, a source of fluid pressure, and pressure responsive means responsive alternately to the fluid pressure and to the hydrostatic pressure of the liquid, the level of which is to be controlled, the pressure responsive means being operable upon the application of the fluid pressure to open the valve and to maintain the valve in an open position until passage therethrough of a quantity of liquid providing a hydrostatic pressure sufficient to operate the pressure responsive means against the action of the fluid pressure and to permit the valve to close.

8. In a well in a producing reservoir having a pressure insufficient to flow the well liquid to the well surface, including a casing, a tubing within the casing, means for directing the well liquid into the tubing, and means operable periodically and independently of the liquid level in the tubing for lifting the well liquid to the surface of the ground; the combination of means for controlling the level of well liquid within the tubing, comprising valve means normally positioned to prevent the flow of liquid therethrough, a source of fluid pressure, pressure responsive means responsive alternately to the fluid pressure and to the hydrostatic pressure of the liquid the level of which is to be controlled, the pressure responsive means being operable upon the application of the fluid pressure to open the valve and to maintain the valve in an open position until passage therethrough of a quantity of liquid providing a hydrostatic pressure offsetting the applied fluid pressure, and means for closing the valve.

9. In a well in a producing reservoir having a pressure insufficient to flow the well liquid to the

well surface, including a casing, a tubing within the casing, means for directing the well liquid into the tubing, and means operable periodically and independently of the liquid level in the tubing for lifting the well liquid to the surface of the ground; the combination of means for controlling the level of well liquid within the tubing, comprising valve means normally positioned to prevent the flow of liquid therethrough, a source of fluid pressure, and pressure responsive means movable in one direction by the application of fluid pressure and in the opposite direction by the hydrostatic pressure of the liquid the level of which is to be controlled, the pressure responsive means opening the valve upon the application of fluid pressure and maintaining the valve in an open position until passage therethrough of a quantity of liquid providing a hydrostatic pressure sufficient to operate the pressure responsive means against the action of the fluid pressure and to permit the valve to close.

10. In a well producing reservoir having a pressure insufficient to flow the well liquid to the well surface, including a casing, a tubing within the casing, means for directing the well liquid into the tubing, and means operable periodically and independently of the liquid level in the tubing for lifting the well liquid to the surface of the ground; the combination of means for controlling the level of well liquid within the tubing, comprising valve means normally positioned to prevent the flow of liquid therethrough, a source of fluid pressure, and pressure responsive means responsive alternately to the fluid pressure and to the hydrostatic pressure of the liquid the level of which is to be controlled, the pressure responsive means comprising a floating piston member movable in one direction by the application of the fluid pressure to open the valve and to maintain the valve in an open position until passage therethrough of a quantity of liquid providing a hydrostatic pressure sufficient to move the floating piston in the opposite direction thereby permitting the valve to close.

11. In a well in a producing reservoir having a pressure insufficient to flow the well liquid to the well surface, including a casing, a tubing within the casing, means for directing the well liquid into the tubing, and means operable periodically and independently of the liquid level in the tubing for lifting the well liquid to the surface of the ground; the combination of means for controlling the level of well liquid within the tubing, comprising valve means normally positioned to prevent the flow of liquid therethrough, a source of fluid pressure, pressure responsive means responsive alternately to the fluid pressure and to the hydrostatic pressure of the liquid the level of which is to be controlled and operable upon application of the fluid pressure to open the valve and maintain the valve in an open position until passage therethrough of a quantity of liquid providing a hydrostatic pressure sufficient to operate the pressure responsive means against the action of the fluid pressure and to permit the valve to close, the pressure responsive means comprising a normally distended bellows, means for applying the fluid pressure externally of the bellows, and means for applying the hydrostatic pressure internally of the bellows.

12. In a well in a producing reservoir having a pressure insufficient to flow the well liquid to the well surface, including a casing, a tubing within the casing, means for directing the well liquid into the tubing, and means operable pe-

riodically and independently of the liquid level in the tubing for lifting the well liquid to the surface of the ground; the combination of means for controlling the level of well liquid within the tubing, comprising valve means normally positioned to prevent the flow of liquid therethrough, a source of fluid pressure, pressure responsive means responsive alternately to the fluid pressure and to the hydrostatic pressure of the liquid the level of which is to be controlled, the pressure responsive means comprising a normally distended bellows, means operably associating the bellows with the valve, means for applying the fluid pressure externally of the bellows whereby the bellows is contracted thereby opening the valve and maintaining the valve in an open position until passage therethrough of a quantity of liquid providing a hydrostatic pressure greater than the fluid pressure, and means applying the hydrostatic pressure internally of the bellows whereby the bellows will be caused to return to its normally distended position thereby permitting the valve to close.

13. The combination with a well tubing having an intermitter control valve connected therein and operable independently of the liquid level in the tubing for controlling the admission of a lifting fluid under pressure into said well tubing, of a liquid level control device connected in said well tubing below said intermitter valve and having means for maintaining the level of the well liquids at a desired point in said tubing.

14. The combination as set forth in claim 13, wherein the liquid level control device includes a main valve which is normally closed to shut off upflow of the well liquids through the tubing, and means actuated when the liquid level in said tubing falls below a predetermined point for opening said valve to allow upflow of the well liquids in said tubing, said last means also functioning when the desired liquid level is restored to close the main valve.

15. A liquid level control device including a well tubing, a housing connected with the tubing provided with a flow passage communicating with the tubing whereby well liquids will flow upwardly through the passage and the tubing, a valve in the passage movable to open and closed position for controlling the upward flow of the liquids in the tubing, biasing means tending to close said valve, a source of fluid pressure, and means in fluid connection with, and responsive alternately to, the fluid pressure and the hydrostatic pressure of the liquid in the tubing for opening the valve when the level of liquid in the tubing falls below a predetermined high point and for permitting said biasing means to close the valve when the level of liquid in the tubing again reaches such high point.

16. The combination with a well conductor having an intermitter control valve connected therein and operable independently of the liquid level in the conductor for controlling the admission of a lifting fluid under pressure into said well conductor, of a liquid level control device connected in said well conductor below said in-

termitter valve and having means for maintaining the level of the well liquids at a desired point in said conductor.

17. The combination with a well conductor having an intermitter control valve connected therein and operable independently of the liquid level in the conductor for controlling the admission of a lifting fluid under pressure into said well conductor, of a liquid level control device connected in said well conductor below said intermitter valve and having means for maintaining the level of the well liquids at a desired point in said conductor, wherein the liquid level control device includes a main valve which is normally closed to shut off upflow of the well liquids through the conductor, and means actuated when the liquid level in said conductor falls below a predetermined point for opening said valve to allow upflow of the well liquids in said conductor, said last means also functioning when the desired liquid level is resorted to close the main valve.

18. An apparatus for flowing wells comprising, a well conductor, an intermitter control valve connected in the conductor and operable independently of the liquid level in said conductor for controlling the admission of a pressure lifting fluid into the conductor at predetermined time intervals, a liquid level control device connected in the conductor below said intermitter valve and having valve means for shutting off the admission of well liquid into the conductor when the level of said liquid rises to a predetermined point in the conductor.

19. A liquid level control device including a well tubing, a housing connected with the tubing provided with a flow passage communicating with the tubing whereby well liquids will flow upwardly through the passage and the tubing, a pressure actuated valve normally maintained in a closed position in the passage for controlling the flow of the liquids in the tubing, a source of fluid pressure, and means responsive alternately to the fluid pressure and to the hydrostatic pressure of the liquids in the tubing for controlling the operation whereby the valve will be opened when the level of the liquids in the tubing falls below a predetermined high point and closed when the level of the liquids in the tubing again reaches such high point.
